BY *Theodore E. Wiedersheim Jr.*

ATTORNEY.

UNITED STATES PATENT OFFICE.

THEODORE E. WIEDERSHEIM, JR., OF PHILADELPHIA, PENNSYLVANIA.

DESIGN FOR A BOX.

SPECIFICATION forming part of Design No. 25,000, dated December 24, 1895.

Application filed November 7, 1895. Serial No. 568,236. Term of patent 3½ years.

To all whom it may concern:

Be it known that I, THEODORE E. WIEDERSHEIM, JR., a citizen of the United States, residing in the city and county of Philadelphia, State of Pennsylvania, have invented and produced a new and original Design for a Box, of which the following is a specification, reference being had to the accompanying drawings, showing a part thereof.

o The leading feature of my design for a box is the representation of a box with a person simulating the carrying of the same.

Figure 1 represents a perspective view of a box embodying my design. Fig. 2 represents a side elevation thereof.

Similar letters of reference indicate corresponding parts in the two figures.

In the drawings, A designates a paper box, and B designates the lid thereof.

C designates a flap on the side of the box, the same representing the figure of a person whose hands are apparently on the box, thus simulating the carrying of the box by the person.

What I claim is—

The design for a box substantially as described and shown.

THEODORE E. WIEDERSHEIM, JR.
